CIGARETTE CASE

George Zint, Wapakoneta, Ohio

Application May 12, 1937, Serial No. 142,256

4 Claims. (Cl. 206—41)

The invention aims to provide an exceptionally simple and inexpensive, yet a very desirable and convenient cigarette case from which the cigarettes may be ejected one at a time with ease.

With the foregoing in view, the invention resides in the novel subject matter hereinafter described and claimed, description being accomplished by reference to the accompanying drawing.

Fig. 1 is a perspective view showing the front of the case, the cover being open.

Fig. 2 is a rear elevation.

Fig. 3 is a horizontal section on line 3—3 of Fig. 1.

Figs. 4 and 5 are vertical sectional views at right angles to each other, as indicated by lines 4—4 and 5—5 of Fig. 3.

One specific form of the invention has been shown in the drawing, formed from metal, but it is to be understood that numerous variations may be made within the scope of the invention as claimed, and that any preferred metallic or non-metallic material may be used in the manufacture of the device.

For purposes of description, the device will be considered as standing upright, for instance, upon a table or the like, but it is to be understood that it is not essential that the device always occupy a vertical position. Moreover, it may be manufactured in a relatively small size for pocket use and in larger sizes for use elsewhere.

The numeral 6 denotes a one-piece continuous vertical wall and 7 has reference to a horizontal plate surrounded by said wall and secured thereto. The plate 7 is located between the upper and lower edges of the wall 6 whereby the upper portion of said wall constitutes one continuous upwardly projecting flange 8, and the lower portion of said wall forms a continuous downwardly projecting flange 9. Vertical tubes 10 are soldered or otherwise secured to each other as denoted at 11, the lower ends of said tubes resting upon and being closed by the plate 7, and being secured within the confines of the upwardly projecting flange 8. The plate 7 is formed with openings 12 communicating with the tubes 10, said openings slidably receiving the downwardly projecting operating stems 13 of a plurality of cigarette ejecting plungers 14, the downwardly projecting stems being all disposed within the confines of the downwardly projecting flange 9 which therefore constitutes a guard preventing accidental striking of or pushing of said stems.

A suitable cover 15 is provided for the upper

ends of the tubes 10, said cover being hinged at 16 to a strip 17 which extends transversely across and is secured to a number of said tubes 10, at the rear of the case. The front of the cover 15 is preferably provided with a downwardly projecting flange 18 having a stamped socket 19 to receive an outwardly stamped detent 20 on one of the tubes 10, for normally holding the cover in closed position.

The cigarettes are loosely received in the tubes 10 and it will be seen that the stems 13 of the plungers 14 may readily be pushed to eject any desired number of the cigarettes in position for total withdrawal from the case, when the cover 15 is opened. The lower ends of the stems 13 are slightly enlarged to prevent them from passing through the openings 12 when the case is inverted.

From the foregoing, taken in connection with the accompanying drawing, the construction disclosed together with its advantages and possibilities, will be readily understood without requiring more explanation, attention however, being again invited to the possibility of making variations and using different materials within the scope of the invention as claimed.

I claim:

1. A cigarette case having a plurality of cigarette-receiving tubes secured side-by-side and each open at one end, fixed closing means for the other end of each of said tubes, said closing means having apertures coaxial with said tubes, cigarette-ejecting plungers slidable in said other ends of said tubes and having stems passing slidably through said apertures, said stems projecting longitudinally from the tubes to be selectively pushed with one finger, and a removable closure for the open ends of said tubes.

2. A cigarette case comprising a continuous wall, a plate surrounded by said wall and secured at its edge thereto, said wall projecting from said plate to provide a continuous guard flange, a plurality of cigarette-holding tubes closed at one end by said plate and secured in fixed relation therewith, said plate having openings communicating with said tubes, and cigarette-ejecting plungers in said tubes having operating stems passing through said openings and disposed within the confines of said guard flange.

3. A cigarette case comprising a continuous wall, a plate surrounded by said wall and secured at its edge thereto, said plate being disposed between the edges of said wall, whereby one edge portion of said wall constitutes one continuous

flange projecting in one direction from said plate and the other edge portion of said wall constitutes another continuous flange projecting in the opposite direction from said plate, a plurality of cigarette-receiving tubes disposed side by side and each having one end disposed within the confines of said one continuous flange, said tubes being secured in fixed relation with said plate and wall and being closed at said one end by said plate, said plate having openings communicating with said tubes, and cigarette-ejecting plungers in said tubes, said plungers having operating stems passing through said openings and dis-

posed within the confines of said other continuous flange.

4. A cigarette case having a plurality of cigarette-receiving tubes disposed side-by-side, said tubes being open at one end, cigarette-ejecting plungers slidably in the other ends of said tubes and projecting longitudinally therefrom to be finger-actuated, a removable closure for the open ends of said tubes, and a continuous guard secured to said tubes and projecting longitudinally therefrom around the projecting portions of the entire group of plungers. 5 10

GEORGE ZINT.
